UNITED STATES PATENT OFFICE.

STEPHEN P. LAPHAM, OF PIKE, NEW YORK.

COMBINED SCREW DRIVER AND HOLDER.

SPECIFICATION forming part of Letters Patent No. 766,270, dated August 2, 1904.

Application filed March 10, 1904. Serial No. 197,445. (No model.)

To all whom it may concern:

Be it known that I, STEPHEN P. LAPHAM, a citizen of the United States, residing at Pike, in the county of Wyoming and State of New York, have invented a new and useful Combined Screw Driver and Holder, of which the following is a specification.

My invention relates to screw-drivers, and has for its objects to produce a comparatively simple inexpensive device of this character having means for engaging and securely holding a screw while being operated upon and to provide for locking said means in engaging position.

To these ends the invention comprises the novel features of construction and combination of parts more fully hereinafter described.

In the accompanying drawings, Figure 1 is a side elevation of my improved device. Fig. 2 is a longitudinal sectional elevation. Fig. 3 is a side elevation showing the driver projected beyond the clamping-jaws. Fig. 4 is a detail section on the line 4-4 of Fig. 1.

Referring to the drawings, 1 designates the screw-driver handle, provided with a cylindrical portion or shank 2, having a central longitudinal opening or socket 3, designed to receive the inner end of the screw-driver shank 4, of which it forms, in effect, a continuation. The outer end of the shank 4 is flattened or otherwise formed, as at 5, for engagement with a screw, while the inner end of the shank 4, which enters the socket 3, is preferably of semicircular form in cross-section and has its flattened side engaged by the correspondingly-flattened portion of a pin 6, extended transversely through the handle-shank 2, whereby the parts are detachably connected and held against relative rotation.

Surrounding the cylindrical portion or shank 2 and slidably longitudinally thereon is a tubular sleeve 7, provided at its forward end with a reduced tubular portion 8, adapted to surround the shank 4 of the screw-driver, the portion 8 being surrounded adjacent to its longitudinal center by a fixed collar 9, forward of which said tube is split to produce a pair of oppositely-disposed spring-jaws 10, constituting screw-engaging and holding members or devices. The jaws 10, which are suit-

ably and reversely bent adjacent to their outer or forward ends to produce a screw-head receiving space or socket 11, are provided in rear of said socket with a pair of coöperating fingers or elements 12, carried, respectively, by the jaws and in advance of the socket, with a pair of inwardly-extending coöperating screw-engaging portions 13 oppositely recessed to conjointly embrace the shank of a screw, the finger 12 of one jaw being extended transversely beyond that of the other, whereby the adjacent end of the driver in moving to engaging position as hereinafter explained will pass between them and serve to draw the jaws together for securely holding the screw.

Provided on the sleeve 7 is a suitable enlargement 15, through which a clamping-screw 16 is tapped with its inner end projecting into a longitudinal slot or seat 17, formed in the shank portion 2. The screw 16, which acts in conjunction with the ends of the slot 17 as an abutment for limiting the longitudinal movement of the sleeve upon the shank, may be manipulated for locking said parts against relative movement and, further, serves as a knob or projection for engagement by the operator in sliding the sleeve back and forth upon the shank 2, whereby the screw performs the threefold function of a stop member, a clamping or locking member, and an operating member for the sleeve.

In practice when it is desired to hold a screw for inserting the same the screw is manipulated to release the sleeve, which latter is then moved forward on the shank, thereby withdrawing the end 5 of the driver from between the screw-engaging portions of the jaws 10. The screw is then inserted between said jaws, and the sleeve is moved rearward on the shank, this action serving to project the driver forwardly between the fingers 12, thereby drawing the jaws together and causing the engaging portions 13 to snugly embrace the shank of the screw. After the end of the driver has been properly seated in the screw-head slot, the clamping member or screw 16 may be manipulated for locking the sleeve against further movement on the shank, thereby securely holding the screw while being operated upon. To remove a screw, the

engaging end of the driver is projected beyond the engaging portions 13 of the jaws by moving the sleeve to its extreme rearward position upon the shank 2. After the screw 5 has been sufficiently loosened the jaws may, if so desired, be engaged therewith in the manner just explained.

From the foregoing it is apparent that I 10 produce a simple device which will admirably perform its functions; but it is to be understood that I do not limit myself to the precise details herein set forth, inasmuch as minor changes may be made without departing from the spirit of the invention.

15 Having thus described the invention, what is claimed is—

1. The combination with a screw-driver, of a pair of screw-engaging members carried thereby, said driver being adapted for longitudinal movement relative to the members, a pair of coöperating elements provided respectively on the members for engagement with the driver to move the members to screw-retaining position, and means for locking the 25 driver against movement.

2. The combination with a screw-driver having a shank, of a sleeve slidable longitudinally of the shank, a pair of screw-engaging members carried by the sleeve for longitudinal movement relative to the driver, means controlled by the movement of the latter for moving the members to screw-retaining position, and means for locking the sleeve against movement.

3. The combination with a screw-driver having a shank, of a sleeve slidable longitudinally of the shank, a pair of screw-engaging members carried by the sleeve for longitudinal movement relative to the driver, means controlled by the relative movement 40 of the parts for moving the members to screw-retaining position, abutments provided on the shank, and a locking device carried by the sleeve for locking the parts against relative movement, said device coöperating with the 45 abutment to limit said movement of the parts.

4. The combination with a screw-driver having a shank and a handle, of a pair of coöperating screw-engaging members carried by and adapted for movement longitudinally 50 of the shank, means controlled by the relative movements of the parts for moving the members to screw-retaining position, and an operating member disposed adjacent to the handle and operatively connected with the 55 screw-engaging members for actuating the latter.

5. The combination with a screw-driver having a shank and a handle, of a pair of screw-engaging members carried by and adapted for longitudinal movement relative to the shank, a pair of coöperating elements carried respectively by the members for engagement with the driver to move the members to screw-retaining position, and an operating member disposed adjacent to the handle and operatively connected with the screw-engaging members for actuating the latter.

In testimony that I claim the foregoing as my own I have hereto affixed my signature in the presence of two witnesses.

STEPHEN P. LAPHAM.
